(57) **CLAIM**

The ornamental design for a charger, as shown and described.

DESCRIPTION

FIG. 1 is a top perspective view from the front left side of a charger showing our new design;

FIG. 2 is a bottom perspective view from the front left side thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a cross-sectional view thereof, taken along line 9-9 of FIG. 3; ps FIG. 10 is a left front perspective view thereof, showing the battery storage portion disengaged, and connector and cable portion in the undocked state;

FIG. 11 is a left rear perspective view thereof, showing the battery storage portion disengaged, and connector and cable portion in the undocked state; and,

FIG. 12 is a perspective view showing the charger is use, wherein the cable portion is plugged into a computer or other electronic device, and a battery pack in position.

The broken lines illustrate environmental structure and form no part of the claimed design.
